UNITED STATES PATENT OFFICE.

ANTHON W. PUTMAN CRAMER, OF WESTFIELD, NEW JERSEY.

TOBACCO-PIPE CLEANER.

1,207,375.

Specification of Letters Patent.

Patented Dec. 5, 1916.

Application filed July 17, 1915. Serial No. 40,380.

To all whom it may concern:

Be it known that I, ANTHON W. PUTMAN CRAMER, a citizen of the United States, residing at Westfield, in the county of Union 5 and State of New Jersey, have invented an Improvement in Tobacco-Pipe Cleaners, of which the following is a specification.

As is well known by all persons who smoke a tobacco pipe, the bowl thereof rapidly becomes incrusted with a lining of carbon, and in order to keep a pipe properly, it should be cleaned of this incrustation regularly.

I am aware that heretofore various devices have been proposed for cleaning the bowls of tobacco pipes, but so far as the same have come to my attention, they are inadequate for properly doing the work, principally because of the liability, due to 15 their shape, of under-cutting the incrustation in the pipe and consequently breaking, cutting, or otherwise damaging the bowl thereof.

The object of my invention is the provision of a tobacco pipe cleaner so constructed that the sides of the cutter head are substantially parallel, in order to make the cut, in cleaning the bowl of the pipe, in alignment with the axis of the bowl, thus obviating the liability of under-cutting the incrustation and consequently injuring the pipe bowl.

I am also aware that heretofore various devices have been adopted for packing the tobacco in the bowl of a pipe. For example, a disk with a handle attached thereto has been employed for this purpose. In the use of such an instrument, however, there is a tendency, not easily avoided, to pack the tobacco so tightly that the pipe will not draw. In designing my improved pipe cleaner, I have therefore so constructed the handle thereof that it may be employed for packing the tobacco into the pipe bowl 40 around the edges of the bowl so as to prevent the tobacco becoming too tightly packed in the pipe.

The pipe cleaner made in accordance with my present invention will be hereinafter 50 more particularly described, in connection with the accompanying drawing, in which—

Figure 1 is a side elevation of a pipe cleaner showing the same applied to a tobacco pipe which is illustrated in perspective. Fig. 2 is a section through a tobacco

pipe showing the pipe cleaner in an end edge elevation to illustrate the manner in which the tobacco may be packed in the bowl. Fig. 3 is a perspective view illustrating my improved pipe cleaner, and Fig. 4 is a section 60 on line 4, 4, Fig. 3.

Referring to the drawing, my improved pipe cleaner preferably comprises a cutter head 10, having a rounded edge 11, which is sharpened from both surfaces, and the 65 substantially parallel sides 12 and 13, the sharpened edge, as clearly indicated in the drawing, extending a material distance into the parallel sides. Extending from the cutter head 10 is a shank 14, and connected 70 thereto is a transverse handle 15, which terminates in substantially circular ends 16 and 17, both of which are of materially larger diameter than the width of the handle.

The hereinbefore described pipe cleaner is 75 preferably stamped up from sheet metal and, as is indicated in Fig. 1, the cutter head 10 may be inserted in the bowl 18 of the pipe 19 and the instrument turned in one or both directions, to remove the cake or lining of carbon which accumulates in a pipe, the substantially parallel side of the cutter head being of the same or nearly the same width as the diameter of the pipe bowl, making it impossible to under-cut the layer 80 of carbon, thereby obviating the possibility 85 of cutting, cracking, or otherwise injuring the pipe.

By reference to Fig. 2, it will be seen that either end of the handle may be employed to pack the tobacco, indicated at 20, in the bowl of the pipe from the edges thereof in such a manner that the tobacco at the center of the bowl is not packed as tightly as that adjacent the walls thereof, so that 95 all the tobacco in the bowl will not be so tightly packed as to prevent the pipe from drawing properly.

I claim as my invention—

As a new article of manufacture, a tobacco pipe cleaner comprising a flat cutter head having a round sharpened edge at one end and parallel noncutting sides, a shank 100 extending therefrom, and a cross piece associated with said shank and being appreciably longer than the width of the cutter head so as to serve as a grip in the use of the article.

Signed by me this 8th day of July, 1915.
A. W. PUTMAN CRAMER.
